UNITED STATES PATENT OFFICE

95,048

DESIGN FOR A GLOVE

George U. Larom, Brightwaters, and Alfred L. Russo, Astoria, N. Y.

Application January 31, 1935, Serial No. 55,178

Term of patent 3½ years

To all whom it may concern:

Be it known that we, George U. Larom and Alfred L. Russo, citizens of the United States, residing, respectively, at Brightwaters, county of Suffolk, State of New York, and at 2308 Newton Avenue, Astoria, city of New York, county of Queens, State of New York, have invented a new, original, and ornamental Design for a Glove, of which the following is a specification, reference being had to the accompanying drawing, forming a part thereof.

Fig. 1 is a front view of a glove showing my design, and

Fig. 2 is a rear view thereof.

The interrupted cross-hatching appearing on the drawing represents substantially solid material.

We claim:

The ornamental design for a glove, as shown and described.

In testimony whereof, we have signed this specification.

GEORGE U. LAROM.
ALFRED L. RUSSO.
